TOOLHOLDER

Jerry H. Drake, Thomasville, Ga., assignor to
Henry M. Herbener, Thomasville, Ga.

Application June 15, 1944, Serial No. 540,389

9 Claims. (Cl. 29—97.5)

My invention relates to holders for tools used for threading, cutting off, key-seating, or the like.

An important object of the invention is to provide a tool holder of the above mentioned character, which will yield to permit of the tool moving from the work, when too much material is being taken off or when an extra hard spot is encountered, or the like.

A further object of the invention is to provide a tool holder of the above mentioned character having means for holding the tool against movement at the selected cutting position, when the tension of the spring controlling the action of the tool is varied.

A further object of the invention is to provide a tool holder of the above mentioned character which is strong and is capable of employing a sufficiently heavy or stiff spring.

A further object of the invention is to provide a tool holder of the above mentioned character, which will have a yielding action, when doing heavy work, while the same may function as a rigid tool holder when doing light work.

A further object of the invention is to provide a tool holder of the above mentioned character which may be used by an inexperienced operator or in connection with automatic machinery, without liability of breaking the tool or cutter.

A further object of the invention is to provide adjustable pivot means for the tool carrying member, wherein the slack caused by wear can be taken up, so that the holder will be precise or true in operation.

A further object of the invention is to provide a tool holder so constructed that the tool carrying member or lever may have a long arm acted upon by the spring, whereby the desired leverage is obtainable, for the proper operation of the device.

Other objects and advantages of the invention will be apparent during the course of the following description:

In accompanying drawings forming a part of this application and in which like numerals are employed to designate like parts throughout the same,

Figure 1 is a side elevation of a tool holder embodying my invention,

Figure 2 is a plan view of the same,

Figure 3 is a front end elevation of the same,

Figure 4 is a rear end elevation of the same,

Figure 5 is a transverse vertical section taken on line 5—5 of Figure 1, and

Figure 6 is a similar view taken on line 6—6 of Figure 1.

In the drawings, wherein for the purpose of illustration is shown a preferred embodiment of my invention, the numeral 10 designates a side-arm, which may be horizontal in use. This side-arm is provided between its ends and preferably nearer its front end, with a horizontal shank 11, rigidly secured thereto. This shank is preferably formed integral with the side-arm 10 and preferably disposed at a right angle thereto and is adapted to be clamped in the tool post 12 of a lathe or other machine.

The side-arm 10 is provided at its forward 15. end with an upstanding projection 13, preferably formed integral therewith and arranged at a right angle thereto in the same plan. The upstanding projection 13 is provided with a horizontal bearing sleeve 14, preferably integral therewith. This bearing sleeve is arranged at the top of the upstanding projection 13 and extends transversely of the projection 13, preferably at a right angle thereto. The bearing sleeve 14 has a cylindrical bore 15. The bearing sleeve 14 projects 20 laterally beyond the upstanding projection 13, upon opposite sides of the same, and the bearing sleeve 14 is provided at one end with a tapered face 16, which is circular in cross-section and decreases in diameter outwardly from the upstanding projection 13. The bearing sleeve 14 is provided in its top with a screw threaded opening 17 to receive a set-screw 18.

A pivoted tool holding member or lever 19 is disposed upon one side of the side-arm 10, in 35 spaced parallel relation thereto. This tool holding member or lever is provided between its ends and nearer its front end with an upstanding projection 20, preferably formed integral therewith and arranged at a right angle thereto. This upstanding projection 20 is provided at its top with a bearing sleeve 21, preferably integral therewith. This bearing sleeve has a tapered recess 22, increasing in diameter outwardly, to snugly receive the tapered face 16. The bearing sleeve 21 also has a tapered recess 23 increasing in diameter outwardly. The reduced ends of recesses 22 and 23 are in communication with a short cylindrical bore 24 of the bearing sleeve 21, as shown. At its top, the bearing sleeve 21 has a hole 25 for receiving a lubricant and leading to the bore 24.

The numeral 26 designates a cylindrical pin which fits snugly within the cylindrical bore 15 and this pin is provided at one end with a head 55 27, which is circular in cross section, and tapers

inwardly, and is adapted to snugly fit within the tapered recess 23. The pin 26 is provided with an upper flat 28, for clamping engagement with the set-screw 18. The pin 26 has a screw-threaded extension 29, for engaging with a nut 30. By manipulating the nut 30 the slack or play between the portions 16 and 21; and 27 and 21 may be properly taken up, so that the tool carrying member or lever 19 is accurately pivoted supported at the top of the projection 20, and after this adjustment is made, the pin 26 is clamped in the selected adjusted position by the set-screw 18. The tool holding member or lever 19 therefore has a short arm 31 projecting forwardly of the pin or pivot 26 and a long arm 32 projecting rearwardly of the same. The arm 32 may therefore be sufficiently long to produce the desired leverage.

The short arm 31 is provided with an opening 33, for receiving the tool 34, arranged to engage the work 35. This tool is clamped in place by a set-screw 36.

At its rear end the member or lever 19 is provided with an upstanding arm 37, preferably formed integral therewith. This upstanding arm is provided at its top with a horizontal or lateral extension 38, provided with a head 39, having a vertical screw threaded opening for receiving an adjusting screw 40. This adjusting screw is arranged to engage a head or disk 41 applied to one end of a heavy stiff compressible coil spring 42. The head or disk 41 has a boss 43 extending into the bore of the coil spring 42. At its lower end, the coil spring 42 engages a lateral extension 44 of the member or lever 19 which is preferably formed integral therewith. The extension 44 carries an upwardly projecting boss 45, extending into the bore of the coil spring 42.

The tool holding member or lever 19 is provided with a stop device, for retaining the tool 34 in the selected cutting elevation when the tension of the spring 42 is changed or adjusted by manipulating the screw 40. This stop device comprises a horizontal arm 46, rigidly secured to the member or lever 19 between the projection 20 and the spring 42. The arm 46 is arranged above the arm 32 and is preferably formed integral with the upper edge of the arm 32. The horizontal arm 46 extends over the side-arm 10, as shown. The arm 46 has a vertical screw threaded opening 47 receiving an adjustable stop-screw 48, to be locked in the selected adjusted position by a lock nut 49. This set-screw is arranged to engage the upper edge of the side arm 10, as shown.

The operation of the device is as follows: The shank 11 is clamped within the tool post 12 of the lathe or like machine and the tool 34 is brought to the selected cutting elevation, which is determined by the adjustment of the stop screw 48 engaging the side-arm 10. By adjusting the stop screw 48 the elevation of the tool 34 may be varied. The coil spring 42 is now placed under suitable tension by turning the screw 40. When the tool 34 is to do heavy work, the spring 42 is placed under high tension. Under normal cutting conditions, the spring 42 will retain the arm 32 in the lowered position and clamp the stop screw 48 against the side-arm 10. However, should the tool 34 cut too deep or take off too much material, or encounter an extra hard spot in the work, the tension of the spring 42 will be overcome and the tool holding member or lever 19 will swing upon the pin 26, whereby

the tool 34 moves from the work, and relieves the strain upon the tool, thus preventing injury to the tool or the work. Should it be desired to change the tension of the spring 42 while the device is in operation and the stop screw 48 is engaging the side-arm 10, the screw 40 is turned to increase the tension upon the spring, but this increased tension cannot move the member or lever 19 with respect to the said arm 10 and hence the elevation of the tool 34 is not varied. When the device is used for light work, the tension of the spring 42 may be such that it will never be overcome, in which event the device will then operate as a rigid tool holder.

It is to be understood that the form of my invention herewith shown and described is to be taken as a preferred example of the same and that various changes in the shape, size, and arrangement of parts may be resorted to without departing from the spirit of my invention or the scope of the subjoined claims.

Having thus described my invention, what I claim is:

1. A tool holder, comprising a side-arm provided between its ends with a lateral shank to be secured to a tool post, a tool holding member disposed upon one side of the side-arm and pivotally mounted between its ends upon the side-arm near one end of the side-arm, the tool holding member having short and long arms extending upon opposite sides of its pivot, an arm mounted upon the opposite end of the side-arm, and a spring engaging the last named arm and the rear end of the long arm of the tool holding member.

2. A tool holder, comprising a side-arm having a laterally extending shank to be secured to a tool post, an upstanding projection carried by the side-arm near one end thereof, a lever disposed upon that side of the side-arm which is remote from the shank, an upstanding projection secured to the lever near one end thereof, means pivotally connecting the upper ends of the projections, an upstanding arm secured to the side-arm near its opposite end and having a lateral projection extending over the lever, a compressible coil spring arranged between the lateral projection and lever, and means to secure a tool to the lever.

3. A tool holder, comprising a side-arm to be secured to a tool post or the like, a tapered element secured to the side-arm, a bearing sleeve having a tapered recess to pivotally receive the tapered element, adjustable means to draw the bearing sleeve axially upon the tapered element, a lever carried by the bearing sleeve, a spring acting against the lever and side-arm, and means to secure a tool to the lever.

4. A tool holder, comprising a side-arm, means to secure the side-arm to a tool post or the like, a bearing sleeve secured to the side-arm and having a tapered face, a second bearing sleeve having tapered recesses in its ends, one tapered recess receiving the tapered face, a pin arranged within the first bearing sleeve and having a tapered head arranged within the other tapered recess, means to adjust the pin axially, means to clamp the pin in the selected adjusted position, an arm carried by the last named sleeve, a spring acting against the arm and side-arm, and means to secure a tool to the arm.

5. A tool holder, comprising a generally horizontal side-arm provided with a shank to be secured to a tool post, a generally horizontal tool holder arranged upon one side of the side-arm and pivotally mounted upon the side-arm to turn

upon a transverse axis with relation to the side arm, an arm secured to the side-arm and having an extension projecting across the tool holder, and a spring arranged between said extension and tool holder.

6. A tool holder, comprising a generally horizontal side-arm provided with a shank to be secured to a tool post, a generally horizontal tool-holding member arranged upon one side of the side-arm, a pivot element arranged near one end of the side-arm and extending transversely through the side-arm and tool-holding member, an upstanding arm secured to the side-arm near its opposite end and provided with a lateral extension extending over the tool-holding member, and a compressible coil spring arranged between the lateral extension and the tool-holding member.

7. A tool holder, comprising a side-arm to be secured to a tool post or the like, a lever arranged near the side-arm and extending longitudinally thereof, a pivot element extending transversely of the side-arm and lever for pivotally connecting the side-arm and lever and arranged near one end of the lever, means arranged near the pivot element for securing a tool to the lever, a spring engaging the lever near its opposite end, adjustable means mounted upon the side-arm and engaging the spring to regulate its tension, and a stop element secured to the lever and arranged to engage the side-arm to limit the movement of the lever upon the transverse pivot element.

8. A tool holder, comprising a side-arm to be secured to a tool-post or the like, a lever arranged near the side-arm and extending longitudinally thereof, a pivot element extending transversely of the side arm and lever for pivotally connecting the side-arm and lever and arranged adjacent to one end of the lever, means arranged adjacent to such end of the lever for securing a tool to the lever, a spring engaging the lever adjacent to its opposite end, adjustable means mounted upon the side-arm and engaging the spring to regulate its tension, and an adjustable stop mounted upon the lever and arranged to engage the side-arm to limit the movement of the lever upon the transverse pivot element.

9. A tool holder, comprising a side-arm provided with a laterally extending shank to be secured to a tool post, a lever disposed upon one side of the side-arm and extending longitudinally thereof, a pivot element connecting the lever and side-arm and extending transversely of the lever and side-arm and arranged near the forward end of the lever, said lever being provided near its forward end with means for holding a cutter, said lever having a long arm, a spring acting upon the rear ends of the side-arm and lever, and a bolt having screw-threaded engagement with the lever and arranged to engage with the side-arm and serving as an adjustable stop.

30

JERRY H. DRAKE.
